Primary Examiner — Anhdao Doan(74) *Attorney, Agent, or Firm* — Knobbe, Martens, Olson & Bear, LLP(57) **CLAIM**

The ornamental design for a tank, as shown and described.

DESCRIPTION

FIG. 1 is an exploded front, right-side perspective view of a tank showing my new design;

FIG. 2 is an exploded rear, left-side perspective view thereof;

FIG. 3 is a front, right-side perspective view thereof;

FIG. 4 is a top plan view thereof;

FIG. 5 is a bottom plan view thereof;

FIG. 6 is a right-side view thereof;

FIG. 7 is a left-side view thereof;

FIG. 8 is a front elevation view thereof; and,

FIG. 9 is a rear elevation view thereof.

The broken lines shown in the drawings represent portions of the tank that form no part of the claimed design.
